DUPLICATOR

Harry C. Walter, Bryn Athyn, Pa.

Application January 27, 1940, Serial No. 315,882

7 Claims. (Cl. 101—131)

This invention is concerned with a method of page to page duplication which is particularly useful in books or pads already bound, such, for instance, as books of account, and the provision of a simple device for this purpose.

No easy and inexpensive method of or device for accomplishing the type of duplication described above has been known. Bookkeepers or auditors, for example, who are frequently under the necessity of transferring material from one page to another in columnar pads or books, have found it necessary to copy their column headings, or other material, by hand, or utilize rubber stamps. Both methods involve considerable time and a chance of errors being made, particularly errors of the type where the column headings become transposed or all the headings of a page may be shifted and hence be out of registry with the previous page. The rubber stamp method is impracticable for most uses, as a different group of stamps would be necessary for each type of job, and the cost is excessive.

Attempts have been made to overcome these difficulties by supplying pages printed with suitable indicia, as for instance printed ledger sheets, but such sheets also have a limited field of usefulness by reason of the many different combinations of headings encountered in practice.

An essential object of my invention is to overcome the aforesaid difficulties by a simple device, easy to operate and inexpensive to manufacture, and in addition I contemplate the provision of a device which may be readily and accurately centered over the working area of the page to be printed. I utilize a gelatine pad of the type found in duplicating machines commonly referred to as "hectographs" or "ditto" machines, in combination with a mount or frame for the pad which normally serves to hold the ink-receiving gelatine pad or other duplicator out of contact with the surface to be printed. This mount, however, is of a character to permit its depression by the operator and the consequent transfer of an impression, and in the preferred form I accomplish the ready centering of the device by making the material of the mount transparent.

More specifically, I provide a jelly pad-receiving mount of elongated concave, or channel form in which the pad is fixed longitudinally of the channel. The side walls of said channel are displaceable outwardly from the pad, and this, preferably with very little pressure when the device is placed in operative position, i. e., with

the open side face downward on the surface to be printed.

In the preferred form of my invention the pad holder may be made of some resilient material such as Celluloid or other suitable resilient plastic substance. However, where greater strength is required, as might be the case should the device support a pad of greater area, for instance, one capable of printing several lines at once, it should be borne in mind that the mount could be made of some other suitable material having a considerable degree of inherent rigidity without departing from the spirit of the invention. It is only necessary that the side walls of the device be made of such a material, or mounted in such a way as to permit their outward displacement in order to bring the jelly pad into contact with the working surface.

How the foregoing objects and advantages are accomplished will be presented more fully in the description making reference to the accompanying drawing, in which—

Fig. 1 is a perspective view of a device constructed in accordance with my invention;

Fig. 2 is a plan view showing the device in operative position upon a sheet of ledger paper; and

Fig. 3 is a section taken on the line 3—3 of Fig. 2.

For greater clarity in showing the arrangement of parts, the device is illustrated in Fig. 1 with the side walls of the concave or channel member disposed upwardly. This is opposite to the position of the device when in use. Indicia to be transferred will be seen in reverse on the pad in Fig. 1.

The gelatin pad, designated by the reference numeral 1, may be held against the bottom of the channel 2, by any convenient means. In the embodiment illustrated, two retaining members 3—3 having side wall engaging portions 4—4 are used for the purpose, as well as the natural adhesion of the pad with the mount. It will be seen, of course, that where the retaining members are utilized, they must be of a flexible material capable of the same degree of displacement as the channel side walls.

The mount 2 is, as set forth above, made of transparent material in order that the gelatin pad may be readily positioned above the space to be printed, see Fig. 2, and the side walls 5—5 of said mount may be then displaced outwardly under pressure from above. To aid in positioning the device, one or more guide marks may be made on a side wall of the mount, two being

shown in the drawing at 6-6. Fig. 2 illustrates the alignment of such guide marks with page rulings when the device is in use.

The operation of the device is as follows: The 5 column headings or other indicia which the operator desires to reproduce, are handwritten or stamped in copy ink on the first page of the pad or book. The jelly pad is then brought into contact with said ink and an impression transferred 10 from the page to the gelatin. Following this, the device is slid across the paper or page until the spot or line to receive the impression is seen through the transparent mount to be correctly aligned with the indicia carried by the pad. The 15 guide marks 6-6, mentioned above, may be found helpful in this positioning, particularly where the pages are vertically ruled.

After the device is lined up, a slight pressure of the fingers will displace the channel side walls, 20 the ink of the pad will be brought into contact with the paper, and an impression transferred. Following this, the pressure may be removed and the inked pad can again be brought out of 25 contact with the paper. This is assisted by reason of the natural resilience of the material of the mount.

It is not applicant's desire to limit his invention to a method of and a device for the transfer of indicia in bound books only. Books of this 30 type were used by way of example in connection with the description, as the invention is believed to result in greater advantages where such books are concerned, but it is obvious that the invention is just as applicable to unbound sheets.

35 I claim:

1. A duplicator of the character described, which includes a transparent hectograph, a transparent backing member on which said hectograph is mounted, and means associated with 40 said backing member and normally serving to maintain said hectograph out of contact with the surface to be printed, said means being displaceable to permit depression of the duplicator and contact of the hectograph with the surface to be printed.

45 2. A duplicator of the character described, which includes a transparent hectograph, a transparent backing member on which said hectograph is mounted, and means associated with 50 said backing member and normally serving to maintain said hectograph out of contact with the

surface to be printed, said means being resilient to permit depression of the duplicator and contact of the hectograph with the surface to be printed.

3. A duplicator of the character described, 5 which includes a transparent hectograph, and a member of substantially channel form in which said hectograph is held, the bottom of said channel being transparent and its side walls being displaceable outwardly to permit depression of the 10 duplicator and contact of the hectograph with the surface to be printed.

4. A duplicator of the character described, 15 which includes a transparent hectograph, a transparent backing member on which said hectograph is mounted, and means associated with said backing member and normally serving to maintain said hectograph out of contact with the surface to be printed, said means being displaceable to permit depression of the duplicator and 20 contact of the hectograph with the surface to be printed.

5. A duplicator of the character described, 25 which includes a transparent hectograph, and a member of substantially channel form in which said hectograph is held, said channel member being transparent and sufficiently resilient to permit depression of the duplicator and contact of the hectograph with the surface to be printed.

6. A duplicator of the character described, 30 which includes a transparent hectograph, and a member of substantially channel form in which said hectograph is held, the bottom of said channel being transparent and its side walls being displaceable outwardly to permit depression of the 35 duplicator and contact of the hectograph with the surface to be printed, said channel member being provided with indicia to facilitate positioning of the same.

7. A method of page-to-page duplication of 40 indicia which comprises the steps of marking a specimen with the desired indicia in copying ink, transferring the indicia to a transparent hectograph, mounting the hectograph in a yieldable transparent mount which is adapted to hold its 45 face clear of the work, successively positioning the mounted hectograph over the pages to be marked, and pressing the mounted hectograph against the pages to transfer the indicia from the hectograph to the pages. 50
